UNITED STATES PATENT OFFICE

122,009

DESIGN FOR A BADGE OR SIMILAR ARTICLE

Oscar A. Doob, New York, N. Y.

Application October 20, 1938, Serial No. 80,572

Term of patent 3½ years

To all whom it may concern:

Be it known that I, Oscar A. Doob, a citizen of the United States and resident of the city, county, and State of New York, have invented a new, original, and ornamental Design for a Badge or Similar Article, of which the following is a specification, reference being had to the accompanying drawing, forming a part thereof, and in which

I claim:

The ornamental design for a badge or similar article, as shown.

OSCAR A. DOOB.
